SPACE-BAND FOR LINE-CASTING MACHINES.

1,210,741.

Specification of Letters Patent.

Patented Jan. 2, 1917.

Application filed December 27, 1915. Serial No. 68,878.

To all whom it may concern:

Be it known that I, JAMES L. WEBB, a citizen of the United States, residing at Tioga, in the county of Grayson and State 5 of Texas, have invented certain new and useful Improvements in Space-Bands for Line-Casting Machines, of which the following is a specification.

This invention relates to improvements in 10 space bands or devices placed between the words in linotype composition to space the words evenly, and while my improved construction is more especially intended for use in connection with lines of matrices, each 15 line carrying characters employed in printing, my novel device may also be employed and operated in the same manner as ordinary space bands used in the Mergenthaler and other types of line casting machines.

20 The object of my improvement is to increase the spacing range between the words in this class of machines, and to this end, I mount two independently movable wedge shaped spacing members upon a stationary 25 wedge shaped space band member, the three wedges when in unison effecting the maximum space between matrices for casting lines of type or slugs. When this space band construction is employed in connection with 30 a line of matrices carrying characters as above, the space band mechanism is free for adjustment, as it is located below the casting space, or the space where the mold is located during the type casting operation.

35 Having thus briefly outlined my invention other objects in view will more fully appear as the description proceeds, and the invention consists in certain constructions, arrangements and combinations of parts that 40 I shall hereinafter fully describe and claim.

For a full understanding of the invention, reference is to be had to the following description and accompanying drawings, in which:

45 Figure 1 is a face view of an assembled space band embodying my invention. Fig. 2 is a side view, and Fig. 3 a back view of the same. Figs. 4 and 5 are side views showing the independently movable space band 50 parts in different relative positions. Fig. 6 is a detail in perspective of the relatively stationary space band part. Figs. 7, 8 and 9 are respectively face, side and back views of one of the independently movable space 55 band parts. Figs. 10, 11 and 12 are respec-

tively face, side and back views of the lower independently movable space band part. Fig. 13 is a central longitudinal section of the construction shown in Fig. 3. Fig. 14 is a cross section taken on the line X X, 60 Fig. 13. Fig. 15 is an enlarged detail view of the bottom section of Fig. 13.

Corresponding and like parts are referred to in the following description and indicated in all the views of the drawings by the same 65 reference characters.

Referring now to the form of construction in detail, the numeral 1 designates a relatively stationary wedge-shaped space band member which may be said to constitute the 70 body part of the device, and it remains stationary in the line of matrices. As illustrated in the drawings, this part 1 is thickest at its upper extremity, and tapers downwardly. To the lower portion of this part 75 is secured a tongue 2 which extends from one side thereof, the side edges of the tongue are of dove-tailed shape which engage guides 3 of corresponding shape formed in a movable wedge shaped band member 4, which is 80 thickest near its lower extremity, and tapers gradually toward its upper extremity. The part 4 coöperates with the stationary member 1 to maintain the opposite surfaces of the two parts in parallel relation during the 85 performance of the spacing function. The tongue 2 has a comparatively wide channel 5, and a narrow channel portion 6, the former enabling the spring 7, and the latter enabling a rivet 8 by which the spring is 90 secured, to pass freely in the respective channels when the member 4 is raised to its extreme height in attaining the maximum expansion attainable by these two parts; the end of the wide channel acting as a stop. 95

The lower portion of the band member 4, on the opposite side from the stationary member 1 is reversely beveled as designated by 9. A dove-tailed tongue 10 is formed on this beveled portion that interlocks with a 100 groove 11 of counterpart shape formed in a second movable space band member 12. A spring latch 13 is riveted or otherwise secured in a channel 14 of this member, and a latch releasing spring 7 is secured in a 105 channel 15 in the member 4. When the lower member 12 is not required for use it is locked in its downwardly extended position upon the member 4, by the latch 13, and otherwise rigidly secured by the beveled end 110

18 of the part 12 fitting over the beveled end 19 of the tongue portion 10; which latter construction also prevents the hanging of their respective points on the matrices 5 when the space band is forced upward in the line. The inwardly curved lip 20 of the lower wedge extends within the channel of the middle wedge and safely guides the matrices over the points of the lower wedge.

10 In describing the operation of this construction, it must be assumed that the wedge shaped part 1 is stationary, and coöperates with the movable wedge shaped part 4, their thinner extremities pointing in opposite directions, and the two parts coöperating with each other to maintain the parallelism between their opposite surfaces. When the desired word spacing function can be attained by the adjustment of the member 4, 20 the part 12 remains inactive. When, however, a greater spacing function is required than can be obtained by the employment of the part 4 in coöperative relation with the part 1, the part 12 is brought into requisition 25 by moving it upwardly, intersecting the casting line or area which, as illustrated in the drawing, is between the dotted lines in Fig. 2. It will be noted that I employ two expanding slides, the lower one remaining 30 locked to the upper one until the upper slide has been raised and expanded nearly to its maximum. It is then automatically unlocked by the spring 7 passing under the stationary member 1, forcing the shoulder 35 16 of the latch 13 out of engagement with the end of the channel 15, which permits the raising of the member 12 until a pin 17 contacts the end of bar 4, when the maximum degree of expansion is attained. When this 40 construction is used with the present commercial linotype machines, the space band operating device must be of special construction, whereby it will become practicable to 45 actuate the space band members independently of each other.

Copies of this patent may be obtained for five cents each, by addressing the "Commissioner of Patents, Washington, D. C."

Having thus described my invention, what I esteem as new and desire to secure by Letters Patent of the United States is:—

1. A space band composed of a relatively stationary part having channels, and a wedge shaped member adjustable and guided thereon, said member having a second wedge shaped member movable independently upon it, the two members being interlocking and guided independently of each other. 55

2. A space band composed of a relatively stationary part, having channels, and a wedge shaped member adjustable and guided thereon, said member having a second wedge shaped member movable independently upon 60 it, both being arranged on the same side of the stationary part and guided independently of each other.

3. A space band, comprising a relatively stationary part having channels, and two members adjustable thereon independently of each other, the two members being wedge shaped, and guided independently of each other during such adjustment, the upper end of the lower wedge being curved inwardly to 70 guide the matrices over the points of the wedge.

4. A space band composed of a relatively stationary part having a fixed wedge-shaped portion intersecting the casting line, a wedge shaped member movable on the stationary part, and a second wedge shaped member movable on the first named movable member and provided with a locking device, and the former member having a spring adapted to 75 release the locking device; the two members being arranged on the same side of the stationary part and guided independently of each other, as herein shown and described. 80

In testimony whereof I affix my signature 85 in presence of two witnesses.

JAMES L. WEBB.
